Patented July 13, 1976

240,487

RACK FOR SKIS AND SKI POLES OR THE LIKE

Ralph A. Blair, 228 N. Atlantic Place,
Boise, Idaho 83704

Filed July 30, 1973, Ser. No. 383,630

Term of patent 14 years

Int. Cl. D6—06

U.S. Cl. D6—125

FIG. 1

FIG. 2

FIG. 3

FIG. 1 is a front elevational view of a rack for skis and ski poles or the like showing my new design, with the skis and ski poles shown in broken lines for illustrative purposes only;

FIG. 2 is an enlarged front perspective view thereof;

FIG. 3 is a rear perspective view thereof on a scale similar to FIG. 1.

I claim:

The ornamental design for a rack for skis and ski poles or the like, substantially as shown and described.
